UNITED STATES PATENT OFFICE.

LOUIS F. BRECHT AND NELSON V. STAMEY, OF SAN FRANCISCO, CALIFORNIA.

STOVE.

1,042,638.

Specification of Letters Patent.

Patented Oct. 29, 1912.

Application filed January 29, 1912. Serial No. 674,136.

To all whom it may concern:

Be it known that we, LOUIS F. BRECHT and NELSON V. STAMEY, citizens of the United States, residing at the city of San Francisco, in the county of San Francisco and State of California, have invented certain new and useful Improvements in Stoves, of which the following is a specification.

Our invention relates to improvements in stoves.

The object of our invention is to provide a stove and especially a cooking stove or range with improved means for heating the same by combustion of oil, particularly crude oil or petroleum, in connection with the use of water in the operation, and which means is simple in construction, and rapid, economical and safe in operation.

To said ends, our invention consists in the novel combination or arrangements of parts shown in the accompanying drawings, described in the following specification, and claimed in the appended claims.

In the drawings, Figure 1 is a front elevation of a stove, being partly broken away to show the arrangement embodying our invention, and Fig. 2 is a sectional view on the line B—B of Fig. 1, showing one side of said arrangement.

In the figures so shown, 1 represents a stove or range having the usual flue 2. A door 3 gives access to a fire-box 4 to heat by the use of any suitable fuel therein the burner plate 5, located above said fire-box and secured by the vertical studs 6 to a tray 7, which is secured as shown in Fig. 2. The said tray 7 is provided with an opening 8 for the passage of the rising heat from the fire-box 4 generated by the use of a suitable fuel to commence the operation of the stove. The burner is fed with oil from pipe 9, which pipe opens by means of its bent portion 15 into elbow 16 of the water pipe 10, a moderate flow of oil 17 in the operation being permitted to run on and drop downwardly from the forward inner surface of said elbow, while a moderate supply of water 18 drops downwardly from the rear inner surface of said elbow, the said oil and water dropping centrally through cylinder or shaft 11 upon burner plate 5, where combustion takes place upon the simultaneous contact of said oil and water upon said plate. Upon combus-

tion taking place heat ascends through openings 20 into passage 12 as shown by the arrows and from which it circulates in the usual manner, and then upwardly and through flue 2.

In order to prevent the oil from spreading too rapidly over the burner plate 5, we construct said burner plate with corrugations 14 and flange 13 forming a wall around the same, the central portion of said burner plate being preferably flat, said flat surface having as a border the said corrugations.

The door 3 is provided so that the burner may be withdrawn for cleaning, the plate 7 supporting the burner plate 5 by standards 6, being slidably secured by supports 21 as shown in Fig. 2. In the drawings the mottled parts 22 indicate fire brick or other suitable stove lining, as separated by the metallic walls 23.

We claim:

1. In a stove a fire-box, a tray over said fire box having an opening, a burner-plate positioned above said opening and out of contact with the tray, and being provided on its upper surface with corrugations and a flange projecting upwardly from its outer edge, a shaft opening downwardly over the burner plate, a pipe for oil and a pipe for water emptying into said shaft, and supports sustaining the burner-plate above said fire box.

2. In a stove a fire-box, a tray over said fire-box having an opening, a burner-plate positioned above said opening and out of contact with the tray over said fire-box, and having its outer upper surface provided with corrugations and a flange projecting upwardly from its edge; a shaft opening downwardly over the burner-plate, and a pipe for oil having an elbow and a pipe for water having an elbow emptying into the shaft, the elbow of the pipe for oil opening into the outer portion of the elbow of the pipe for water.

In testimony whereof we affix our signatures in presence of two witnesses.

LOUIS F. BRECHT.
NELSON V. STAMEY.
